ROLLER TRUNNION AND PROCESS OF
MAKING THE SAMEWalter J. Stuber, Philadelphia, Pa., assignor to
Carey-McFall Co., Philadelphia, Pa., a corpora-
tion of Pennsylvania

Application October 3, 1932. Serial No. 636,072

23 Claims. (Cl. 156—36)

This invention relates to an improved form of trunnion or pivot for spring-loaded rollers such as those employed in hanging window shades, automobile curtains, etc.

5 The object of the present invention is to provide a highly efficient form of trunnion and a method by which the trunnions may be produced in quantity at low cost on automatic machinery. Another object of the invention is to construct 10 a trunnion of the type noted as a single piece, including a head adapted to be non-rotatably secured in a roller-supporting bracket, a ratchet portion adapted to be engaged by the pawls in and carried by the barrel of the roller, a shank 15 providing a bearing for the pawl carrier in the barrel of the roller to support the roller in rotatable relation to the trunnion, and an anchorage on the shank for one end of the roller-operating spring having its opposite end anchored to the 20 barrel or to the pawl carrier in the barrel of the roller.

The present application constitutes a continuation in part of the applicant's prior application, Serial No. 580,706, filed December 12, 1931, and 25 is a companion to the applicant's copending applications, Serial No. 636,071, and Serial No. 636,073, respectively filed on October 3, 1932.

In the accompanying drawings:

30 Fig. 1 is a perspective view of one form of trunnion made according to the present invention;

Fig. 2 is a side elevation of the trunnion shown in Fig. 1;

35 Fig. 3 is a plan view of the trunnion shown in Figs. 1 and 2;

Fig. 4 is a transverse sectional elevation taken on the line 4—4, Fig. 2;

40 Fig. 5 is a view illustrating the successive steps attending the manufacture of the trunnions shown in Figs. 1 to 4 inclusive from a bar of stock material;

Fig. 6 is a fragmentary view of a modified form of trunnion;

45 Fig. 7 is a view of another modification of the invention;

Figs. 8 and 9 are respectively a side elevation and plan view of another variation within the scope of the invention;

50 Fig. 10 is a transverse sectional elevation taken on the line 10—10, Fig. 8;

Fig. 11 is a fragmentary view of the blank from which the trunnion shown in Figs. 8 to 10 inclusive is formed;

55 Figs. 12 and 13 are respectively a side eleva-

tion and plan of still another variation of the trunnion;

Fig. 14 is a transverse sectional elevation taken on the line 14—14, Fig. 12; and

Fig. 15 is a fragmentary view of the blank from 60 which the trunnion of Figs. 12, 13 and 14 is formed.

The trunnion shown in Figs. 1 to 5 inclusive comprises a head 1 which is of a rectangular cross section and arranged to be non-rotatably sup- 65 ported in a bracket or hanger as disclosed in the copending applications above noted. In some instances the end 2 of the head 1 functions as an abutment or shoulder for positioning the trunnion in its supporting bracket, so that the end of the 70 roller and the edge of the curtain thereon will be in a definitely spaced relation to the adjacent face of the supporting bracket, while in other instances, as will be noted hereinafter, other portions of the head or appendages thereto func- 75 tion in such capacity.

Formed integral with the head 1 at the end opposite the end 2 thereof is a ratchet portion 3 which is provided with indentations 4 and 5 on its opposite faces respectively adjacent the op- 80 posite edges respectively which serve as ratchet teeth for cooperation with the pawls of the roller.

As shown clearly in Fig. 4, the ratchet portion 3 is of the same thickness as the head 1 but of lesser width than said head, and the ratchet 85 portion 3 is twisted about the longitudinal axis x of the trunnion to a plane disposed anywhere from forty-five to ninety degrees with respect to the plane of the head 1, which latter, when the trunnion is in the roller-supporting position, is 90 preferably disposed in an approximately vertical position. It is preferred to twist the ratchet portion 3 as nearly to a ninety degree relation to the head as possible, in order to present one of the ratchet teeth or indentations 4 and 5 in 95 the most favorable position to be engaged by and to retain one of the pawls of the roller in a practical position to prevent rotation of the roller by its actuating spring. For all practical purposes, and in order to reduce to a minimum the 100 chances of fracturing the metal in or adjacent the twisted area 6, which for purposes of description may be termed the neck of the trunnion, a twist of seventy degrees has been found to be entirely satisfactory.

Formed integral with the ratchet portion 3 and extending parallel to the axis of the trunnion is the shank 7 thereof, which, in the present instance, is of a rectangular cross section disposed in the same general plane as the ratchet portion 110

3 but having a lesser width than the ratchet portion 3, whereby shoulders 8, 8 are provided on the trunnion which limit the movement of the roller bearing, afforded by the pawl carrier of 5 the roller, longitudinally of the trunnion in a direction toward the head 1 of the trunnion. This bearing of the roller is adapted to rotate freely on a bearing portion 9 of the trunnion disposed immediately adjacent the shoulders 8, 10 afforded by the ratchet portion 3. The said bearing of the roller is adapted to engage and turn on and about the corners 10, 10 of the bearing portion 9 of the trunnion, the bore of the bearing being of sufficient size to permit of free 15 rotation about the said rectangular portion 9 of the trunnion.

The bearing portion 9 of the trunnion merges into a tapered spring anchorage portion 11 of 20 rectangular cross section, wherein the corners 12, 12 are notched as at 13, 13 in offset relation to provide a screw thread effect adapted to cooperate with the convolutions of the end of the roller-operating spring to facilitate the assembling of 25 the spring and the trunnion. As the tapered screw threaded end of the trunnion is threaded into the end of the spring the convolutions of the 30 spring enter the notches 13 in the edges of the trunnion and the tapered form of this portion of the trunnion causes the successive convolutions of 35 the spring to expand radially, thus increasing the frictional grip between the trunnion and the spring to such an extent that for all practical operating purposes the spring becomes rigidly attached to the trunnion. The leading end of the 40 spring finally runs onto and firmly grips the non-tapered portion 9 of the trunnion shank and forms an abutment for the pawl carrier, in which the said bearing of the roller is formed, at the side of the carrier opposite to that which bears 45 against the shoulders 8, 8, thus the pawl carrier is limited in its movement on the bearing portion 9 of the shank between the shoulders 8, 8 and the end of the operating spring.

In some instances the trunnion may be provided with an additionally reduced rectangular cross sectional appendage in axial alignment with 50 the shank 7 of the trunnion, as illustrated at 14 in Fig. 7, for providing a second bearing for the trunnion in the barrel of the roller to stabilize the trunnion in the roller under certain conditions. The said second bearing in the roller may be provided to bear on any desired portion of 55 the appendage 14, preferably that portion immediately adjacent the outer end thereof, beyond the end of the spring, and if a single coil spring is used the said second bearing may be provided by a plate secured in the barrel of the roller, when a hollow metal cylindrical roller barrel is 60 used, to which the second end of the spring is secured. In cases of wooden rollers using single or double coil springs the body of the roller at the end of the bore in which the spring is located may be counterbored for the reception of 65 the end of the appendage 14, to provide a bearing therefor.

In instances such as shown in Figs. 8, 9, 10 and 11, the neck 6a, between the head 1a and ratchet portion 3a, to which the twist between 70 the two is confined, is of a lesser width than the head 1a and of greater width than the ratchet portion 3a. In this instance the twisted neck 6a forms a second bearing surface in the roller which in this case is provided by the cap or other closure at the end of the roller which secures 75 the pawl carrier in the roller and hides

the pawls from view. The twist in the neck 6a tends to circumferentially elongate the bearing surface afforded thereby so that such bearing surface is distributed over a greater number of degrees around the trunnion than is the case where a bearing engages a non-twisted rectangular portion of the trunnion.

The shank 7a, like the shank 7 in Fig. 1, affords a bearing portion 9a adjacent the limiting shoulders 8a and the outer end 11a of the shank is tapered to receive the end of the roller-actuating spring, but, in the instance shown in Figs. 8 and 9, the tapered portion 11a is not screw threaded. In this instance the tapered end 11a of the shank is merely forced into the end of the spring which is expanded thereby and grips the shank firmly on the corners thereof. This construction, however, does not afford the finer degree of adjustment between the spring and the shank that will permit the distance between the shoulders 8a and the end of the spring to be accurately determined to obtain the best running fit for the bearing afforded by the pawl carrier which rotates on the shank portion 9a between the shoulders 8a and the end of the spring.

In instances where the trunnion is used in connection with a supporting bracket having a plate in which an opening is formed to receive the rectangular head 1, and wherein a shield is provided to hide the end of the trunnion from view, the end 2 of the trunnion head 1 may pass through the supporting plate of the bracket and bear against the inner surface of the shield, to determine the distance between the end of the roller and the bracket.

In other instances where no shield is employed on the supporting bracket, the twist in the neck 6 or 6a may function as a shoulder, as indicated at 2a, to limit the movement of the trunnion in one direction relative to the bracket to space 115 the end of the roller definitely from the bracket; and in other instances the head of the trunnion may be provided with laterally projecting ears 15, 15 as shown in Fig. 6, providing limiting shoulders 2b, 2b on the trunnion.

In some instances as in Figs. 12 to 15, the neck 6c may be reduced to a width less than the width of the ratchet portion 3c to facilitate the twisting of the head 1c relative to the said ratchet portion 3c, whereby the greatest degree of relative twist 125 may be accomplished with the least possibilities of fracturing the metal of or adjacent the neck.

The method by which the trunnion in each instance noted above is formed is substantially the same and varies only in the amount of metal 130 removed from the bars of stock from which the various forms of trunnions are produced.

The trunnion illustrated in Figs. 1 to 4 is produced from a bar of stock of rectangular cross section 20, shown in Fig. 5, and which is of a width and thickness substantially equal to the width and thickness of the head 1 of the trunnion. The bar 20 is fed to a position A in a punch press of any desired make having cooperating punches and dies capable of producing the ratchet indentations 4 and 5 in opposite faces respectively of the bar. The bar then advances to position B in a second punch press, or to a second set of punches and dies in the same punch press, whereby portions 21, 21 are removed from opposite edges respectively of the bar 20 to provide for the reduction in the width of the ratchet portion 3 of the trunnion relative to the width of the head 1 thereof.

The bar advances then to position C, wherein

140

145

150

portions 22, 22 of the opposite edges respectively of the bar are removed by another set of punches and dies to effect reduction in the width of the shank 7 of the trunnion below the width of the ratchet portion 3.

5 In position D, the shank 7 is subjected to the cooperative action of a set of dies by which the notches 13, 13 are formed in the edges 12, 12 of the tapered portion 11 of the shank 7.

10 At position E the head 1 is twisted relative to the ratchet portion 3 and shank 7 of the trunnion. This twisting may be performed by any desirable or available means, but preferably is produced by a set of relatively movable dies having flat horizontal surfaces arranged parallel to each other for gripping the ratchet portion 3 and shank portion 7 flatly therebetween and adjacent such surface the cooperating dies may have cooperating surfaces disposed at an angle to those arranged to grip the ratchet portion 3 and shank 7, whereby when the dies move one toward the other, common in vertical punch presses, the inclined surfaces will engage the head portion 1 of the trunnion while the horizontal surfaces are engaging the ratchet portion 3 and shank 7 of the trunnion, thus the head 1 will be twisted relative to the ratchet portion 3 and shank 7 about the longitudinal dies of the bar and the trunnion being thus operated upon. In order to allow the neck 6 to twist without interference the horizontal surfaces adapted to engage the ratchet and shank portions of the trunnion are preferably spaced from the relatively inclined surfaces adapted to engage the head 1 of the trunnion.

30 The trunnion is then complete and upon the next advance of the bar 20 moves to position F wherein the preceding finished trunnion is severed along the line z—z from the trunnion occupying position F.

40 In making the trunnion shown in Fig. 6, the bar of stock would have a width corresponding to the measurement from end to end of the ears 15, 15 in a direction transverse of the trunnion and the reduction of the bar to the width of the head 1 by removal of portions 23, 23 (see Fig. 6) may be effected simultaneous with the removal of the portions 21, 21 of the bar in position B or in a separate operation before or after the removal of the portions 21, 21.

50 Likewise in forming the trunnion shown in Figs. 12 to 15, the portions 24, 24 may be removed at the same time as the portions 21, 21.

55 The same is true in regard to the removal of portions 25, 25 in forming the trunnion shown in Figs. 8 to 11 to reduce the width of the neck 6a to a width intermediate that of the head 1a and the ratchet portion 3a.

I claim:

60 1. A trunnion for a roller provided with a pawl for arresting rotation of the roller in one direction about the axis of the trunnion, said trunnion consisting solely of a bar rectangular in cross section and comprising a head portion affording non-rotative support for the trunnion, and a toothed portion axially aligned with the head portion for ratchet engagement with the pawl.

70 2. A trunnion for a roller provided with a pawl for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, and a bearing

portion axially aligned with the head and ratchet toothed portions affording rotative support for the roller on the trunnion.

3. A trunnion for a roller provided with a pawl for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, and a shank axially aligned with the head and ratchet toothed portions affording anchorage for one end of a spring adapted to rotate the roller in said direction about the axis of the trunnion.

80 4. A trunnion for a roller provided with a pawl for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a shank axially aligned with the head and ratchet toothed portions affording a bearing surface for the roller adjacent said ratchet toothed portion and a tapered end on said shank beyond said bearing surface affording anchorage for one end of a spring adapted to rotate the roller in said direction about the axis of the trunnion.

85 5. A trunnion for a roller provided with a pawl for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a shank axially aligned with the head and ratchet toothed portions affording a bearing surface for the roller adjacent said ratchet toothed portion and a tapered screw-threaded end on said shank beyond said bearing surface, affording anchorage for one end of a spring adapted to rotate the roller in said direction about the axis of the trunnion.

90 100 105 110 115 120 125 130 135 140 145 150

6. A trunnion for a roller provided with a pawl for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, said ratchet toothed portion being twisted circularly about the axis of the trunnion to a plane disposed at an angle to that of the head portion.

7. A trunnion for a roller provided with a pawl for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, and a neck portion axially aligned with the head and ratchet toothed portions and disposed intermediate said portions, said ratchet portion being twisted circularly about the axis of the trunnion to a plane disposed at an angle to that of said head portion, said twist taking place in said neck portion.

8. A trunnion for a roller provided with a pawl for arresting rotation of the roller in one direction about the axis of the trunnion, said trunnion consisting solely of a bar rectangular in cross section and comprising a head portion affording

non-rotative support for the trunnion, a toothed portion axially aligned with the head portion for ratchet engagement with the pawl, a neck portion axially aligned with the head and ratchet toothed portions and disposed intermediate said portions, said ratchet portion being twisted circularly about the axis of the trunnion to a plane disposed at an angle to that of said head portion; said twist taking place in said neck portion, and a shoulder afforded by one of said portions for engagement with a bracket supporting said trunnion to limit axial movement of the trunnion in one direction relative to the bracket.

9. A trunnion for a roller provided with a pawl 15 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a neck portion axially aligned with the head and ratchet toothed portions and disposed intermediate said portions, said ratchet portion being 20 twisted circularly about the axis of the trunnion to a plane disposed at an angle to that of said head portion, said twist taking place in said neck portion, and a shoulder afforded by the twisted neck portion for engagement with a bracket supporting said trunnion to limit axial movement of the trunnion in one direction relative to the bracket.

10. A trunnion for a roller provided with a pawl 35 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a neck portion axially aligned with the head and ratchet toothed portions and disposed intermediate said portions, said ratchet portion being 40 twisted circularly about the axis of the trunnion to a plane disposed at an angle to that of said head portion, said twist taking place in said neck portion, and a shoulder on the head portion for engagement with a bracket supporting said trunnion to limit axial movement of the trunnion in one direction relative to the bracket.

11. A trunnion for a roller provided with a pawl 55 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, and a neck portion axially aligned with the head and ratchet toothed portions and disposed intermediate said portions, said ratchet portion being 60 twisted circularly about the axis of the trunnion to a plane disposed at an angle to that of said head portion, said twist taking place in said neck portion and affording a bearing surface for the roller on the trunnion.

12. A trunnion for a roller provided with a pawl 70 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a neck portion axially aligned with the head and

ratchet toothed portions and disposed intermediate said portions, said ratchet portion being twisted circularly about the axis of the trunnion to a plane disposed at an angle to that of said head portion, said twist taking place in said neck portion and affording a bearing surface for the roller on the trunnion, and a portion axially aligned with the head and ratchet toothed portion and affording a second bearing for the roller on the trunnion.

13. A trunnion for a roller provided with a pawl 80 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a neck portion axially aligned with the head and ratchet toothed portions and disposed intermediate said portions, said ratchet portion being twisted circularly about the axis of the trunnion to a plane disposed at an angle to that of said head portion, said twist taking place in said neck portion and affording a bearing surface for the roller on the trunnion, and a portion axially aligned with the head and ratchet toothed portion and affording a second bearing for the roller on the trunnion immediately adjacent the ratchet toothed portion.

14. A trunnion for a roller provided with a pawl 90 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, a neck portion axially aligned with the head and ratchet toothed portions and disposed intermediate said portions, said ratchet portion being twisted circularly about the axis of the trunnion to a plane disposed at an angle to that of said head portion, said twist taking place in said neck portion and affording a bearing surface for the roller on the trunnion, and a portion axially aligned with the head and ratchet toothed portion and affording a second bearing for the roller on the trunnion immediately adjacent the ratchet toothed portion.

15. A trunnion for a roller provided with a pawl 100 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, and a bearing portion axially aligned with the head and ratchet toothed portions affording rotative support for the roller on the trunnion immediately adjacent the ratchet toothed portion and at a point removed from said ratchet toothed portion.

16. A trunnion for a roller provided with a pawl 110 for arresting rotation of the roller in one direction about the axis of the trunnion, said trunnion consisting solely of a bar rectangular in cross section and comprising a head portion affording non-rotative support for the trunnion, a toothed portion axially aligned with the head portion for ratchet engagement with the pawl, and a bearing portion axially aligned with the head and ratchet toothed portions affording rotative support for the roller on the trunnion immediately adjacent the ratchet toothed portion and at a point removed from said ratchet toothed portion, and a tapered portion intermediate the two said rotative supports affording anchorage for one end of a spring adapted to rotate the roller about the axis of the trunnion.

17. A trunnion for a roller having an actuating spring and stop pawl, said trunnion consisting of a bar of rectangular cross section and comprising a head portion of predetermined width for non-rotatably supporting the trunnion in a roller-hanging fixture, a ratchet toothed portion of lesser width than the head portion axially aligned with and circularly twisted with respect to the head portion and provided with indentations forming the ratchet teeth for engagement by the pawl, and a shank portion of lesser width than the ratchet toothed portion axially aligned with the head and ratchet toothed portions and tapered adjacent its end remote from the ratchet 140

toothed portion affording an anchorage for one end of the spring.

17. A trunnion for a roller having an actuating spring and stop pawl, said trunnion consisting of a bar of rectangular cross section and comprising a head portion of predetermined width for non-rotatably supporting the trunnion in a roller-hanging fixture, a ratchet toothed portion of lesser width than the head portion axially aligned

10 with and circularly twisted with respect to the head portion and provided with indentations forming the ratchet teeth for engagement by the pawl, a shank portion of lesser width than the ratchet toothed portion axially aligned with the head and ratchet toothed portions and tapered adjacent its end remote from the ratchet toothed portion affording an anchorage for one end of the spring, and a neck portion intermediate the head and ratchet toothed portions and of lesser width than either thereof wherein the twist between the head and ratchet toothed portions occurs.

18. A trunnion for a roller having an actuating spring and stop pawl, said trunnion consisting of a bar of rectangular cross section and comprising a head portion of predetermined width for non-rotatably supporting the trunnion in a roller-hanging fixture, a ratchet toothed portion of lesser width than the head portion axially aligned with and circularly twisted with respect to the head portion and provided with indentations forming the ratchet teeth for engagement by the pawl, a shank portion of lesser width than the ratchet toothed portion axially aligned with the head and ratchet toothed portions and tapered adjacent its end remote from the ratchet toothed portion affording an anchorage for one end of the spring, and a neck portion intermediate the head and ratchet toothed portions and of lesser width than either thereof wherein the twist between the head and ratchet toothed portions occurs.

30 19. A trunnion for a roller having an actuating spring and stop pawl, said trunnion consisting of a bar of rectangular cross section and comprising a head portion of predetermined width for non-rotatably supporting the trunnion in a roller-hanging fixture, a ratchet toothed portion of lesser width than the head portion axially aligned with and circularly twisted with respect to the head portion and provided with indentations forming the ratchet teeth for engagement by the pawl, and a shank portion of lesser width than the ratchet toothed portion axially aligned with the head and ratchet toothed portions and tapered adjacent its end remote from the ratchet toothed portion and provided with notches along the corners of its rectangular cross section affording a screw-threaded anchorage for one end of the spring.

40 20. A trunnion for a roller having an actuating spring and stop pawl, said trunnion consisting of a bar of rectangular cross section and comprising a head portion of predetermined width for non-rotatably supporting the trunnion in a roller-hanging fixture, a ratchet toothed portion of lesser width than the head portion axially aligned with and circularly twisted with respect to the head portion and provided with indentations forming the ratchet teeth for engagement by the pawl, and a shank portion of lesser width than the ratchet toothed portion axially aligned with the head and ratchet toothed portions and

tapered adjacent its end remote from the ratchet toothed portion and provided with notches along the corners of its rectangular cross section affording a screw-threaded anchorage for one end of the spring, said shank intermediate said tapered portion and the ratchet toothed portion affording a bearing surface for the roller on the unnotched corners of the rectangular cross section of the shank.

21. The method of producing roller trunnion bars which comprises the removal of predetermined portions of stock along the opposite longitudinal edges of a bar of rectangular cross section to form head, ratchet and shank portions of the trunnion, and twisting the bar circularly about its longitudinal axis intermediate the head and ratchet portions.

22. The method of producing roller trunnion bars which comprises the removal of corresponding portions of stock along the opposite edges respectively of a bar of rectangular cross section to form head, ratchet and shank portions of a trunnion, indenting the ratchet portion to produce teeth therein, and twisting the bar circularly about its longitudinal axis intermediate the head and ratchet portions to obtain a predetermined angular relation between the plane of the head portion and that of the ratchet portion.

23. The method of producing roller trunnion bars which comprises the removal of corresponding portions of stock along the opposite edges respectively of a bar of rectangular cross section to form head, ratchet and shank portions of a trunnion in progressively decreasing widths, indenting the ratchet portion to produce teeth therein, notching the corners of the rectangular shank to provide a screw thread thereon, and twisting the bar circularly about its longitudinal axis intermediate the head and ratchet portions to obtain a predetermined angular relation between the plane of the head portion and that of the ratchet portion.

24. The method of producing roller trunnion bars which comprises the removal of corresponding portions of stock along the opposite edges respectively of a bar of rectangular cross section to form head, ratchet and shank portions of a trunnion, indenting the ratchet portion to produce teeth therein, twisting the bar circularly about its longitudinal axis intermediate the head and ratchet portions to obtain a predetermined angular relation between the plane of the head portion and that of the ratchet portion, and severing the trunnion on a line transversely of the bar at the juncture of the end of the shank of the one trunnion and the head of the next trunnion formed in successive order along the bar.

25. The method of producing roller trunnions which comprises the removal of corresponding portions of stock along the opposite edges respectively of a bar of rectangular cross section to form head, ratchet and shank portions of a trunnion in progressively decreasing widths, indenting the ratchet portion to produce teeth therein, notching the corners of the rectangular shank to provide a screw thread thereon, twisting the bar circularly about its longitudinal axis intermediate the head and ratchet portions to obtain a predetermined angular relation between the plane of the head portion and that of the ratchet portion, and severing the trunnion on a line transversely of the bar at the juncture of the end of the shank of the one trunnion and the

head of the next trunnion formed in successive order along the bar.

26. The method of producing roller trunnion bars which comprises the removal of corresponding portions of stock along the opposite respective edges of a rectangular bar to form head, neck, ratchet and shank portions of a trunnion in the bar with the head, ratchet and shank portions of progressively decreasing widths and the neck of approximately the same width as the shank, and twisting the bar circularly about its longitudinal axis at the narrowed neck portion of the trunnion to place the plane of the ratchet portion of the trunnion at a predetermined angle with respect to the plane of the head portion.

27. The method of producing roller trunnion bars which comprises the removal of corresponding portions of stock along the opposite respective edges of a rectangular bar to form head, neck, ratchet and shank portions of a trunnion in the bar with the head, ratchet and shank portions

of progressively, decreasing widths and the neck of approximately the same width as the shank, indenting the opposite faces of the bar at opposite sides of the longitudinal center of the bar within the ratchet portion of the trunnion to provide ratchet teeth thereon, and twisting the bar circularly about its longitudinal axis at the narrowed neck portion of the trunnion to place the plane of the ratchet portion of the trunnion at a predetermined angle with respect to the plane of the head portion.

28. A trunnion for a roller provided with a pawl for arresting rotation of the roller in one direction about the axis of the trunnion, said trunnion consisting solely of a bar rectangular in cross section and comprising a head portion affording non-rotative support for the trunnion, and a ratchet portion axially aligned with the head portion for ratchet engagement with the pawl.
